UNITED STATES PATENT OFFICE.

EUGÉNE FRANÇOIS SUTER, OF LONDON, ENGLAND.

HAIR CURLER OR ROLLER.

1,266,880.

Specification of Letters Patent. Patented May 21, 1918.

Application filed August 6, 1917. Serial No. 184,766.

To all whom it may concern:

Be it known that I, EUGÉNE FRANÇOIS SUTER, residing at London, England, have invented certain new and useful Improvements in Hair Curlers or Rollers, of which the following is a specification.

My invention relates to an improved hair curler or roller for use in connection with dressing natural hair on the head so as to permanently wave the same.

In dressing hair for permanent waving it is requisite to secure the same in tightly wound coils for subsequent treatment, and especially near the roots, where the hair is thickest and most abundant and difficult to wave effectively, the object of my present invention being to provide an improved compact and reliable curler or roller specially adapted for this purpose.

Such improved hair curler or roller consists of a loose sleeve which has a reduced neck portion at one end, and is mounted on a relatively fixed spindle whereon it rotates, and is controlled by a ratchet and pawl mechanism so that such sleeve can be turned on the spindle in one direction only. The spindle is provided with a slotted extension that projects beyond the reduced neck portion of the sleeve, which is plugged at its outer end, and preferably contains a suitable lubricant, to prevent corrosion of the curler.

The hair to be dressed is secured near its roots to the slotted extension of the spindle, and is coiled around and secured to the sleeve. The curler is then firmly held by the slotted extension while the sleeve is rotated so as to tighten the hair coiled thereon, the ratchet mechanism controlling the sleeve preventing the tension being relaxed, while the reduced neck portion of the sleeve coils the hair most closely near the roots, where it is thickest and difficult of access, so enabling the whole length of hair so coiled to be effectively dressed with a fine permanent wave.

My invention is further described with reference to the accompanying drawings, wherein similar reference numerals indicate like parts.

Figure 1, is an external view of a hair curler or roller made according to my present invention, and Fig. 2, is a sectional view thereof in plan, drawn to a larger scale.

Figs. 3, 4, 5, 6 and 7, are detail views

illustrating the construction of the sleeve and spindle presently referred to.

1, is the sleeve having a reduced neck portion 2, and 3, is the spindle whereon such sleeve is mounted. The reduced neck 60 portion 2, of the sleeve, is formed by a separate tube which is provided with ratchet teeth 2^a, at one end as shown at Fig. 3, and is mounted on the spindle 3, so that its opposite end abuts on the boss or extension 4, formed on one end of such spindle, see Figs. 2 and 5. The ratchet teeth 2^a, are engaged by a detent 5, which works in a slot 6, formed in the spindle 3, as shown at Fig. 4, such detent being held up to the ratchet 65 teeth 2^a, by a spring 7, arranged on the spindle 3, between a sliding collar 8, and a fixed collar 9, as indicated at Figs. 2 and 5. The sleeve 1, is tapered at one end so as to fit over the tube forming the reduced 75 neck portion 2, to which it is brazed or otherwise secured so as to inclose the ratchet teeth 2^a, and the adjacent parts of the spindle 3, and to prevent corrosion of the same. The sleeve 1 is sealed at its outer end 1^a, 80 as indicated at Fig. 2, and preferably contains a suitable lubricant.

The extension 4, of the spindle is slotted laterally with an inclined slot 4^a, and is recessed or curved as indicated at 4^b, Figs. 5 85 and 7, so as to facilitate binding the hair thereto as closely to the roots as possible, while to obtain a fine adjustment of the ratchet mechanism controlling the sleeve 1, an odd number of teeth 2^a, is preferably 90 employed in conjunction with a double acting detent, such as the detent 5, illustrated.

I claim as new and desire to secure by Letters Patent:

1. A hair curler or roller for use in permanently waving hair comprising a loose sleeve provided with a reduced neck portion at one end, and a spindle whereon said sleeve is mounted so that said neck portion abuts on a boss or extension at one end of said 95 spindle, in combination with a spring controlled ratchet mechanism, which is completely inclosed by said sleeve, and is arranged so as to hold said sleeve on said spindle, while allowing of the relative rotation thereof in one direction only.

2. A hair curler or roller adapted for use in permanently waving hair, comprising a sleeve that is furnished with internal ratchet teeth, and comprises a reduced neck portion 110

with a tapered tubular extension that is sealed at its outer end, said sleeve being mounted loose on a spindle in combination with a spring controlled detent arranged so as to engage said ratchet teeth, and a boss or extension on said spindle that projects beyond, and forms an abutment for said sleeve.

3. A hair curler or roller adapted for use in permanently waving hair, comprising a sleeve with a reduced neck portion formed by a narrow end tube that is furnished with an odd number of ratchet teeth and carries

a tapered tubular extension, closed at its outer end and arranged so as to inclose said ratchet teeth, said sleeve being mounted loose on said spindle in operable combination with a spring controlled double acting detent so as to turn in one direction only, a boss or projection on said spindle that extends beyond and forms an abutment for the said neck of said sleeve, and a lateral inclined slot formed in said boss substantially as hereinbefore described. 15 20

EUGÉNE FRANÇOIS SUTER.
